UNITED STATES PATENT OFFICE.

CHARLES H. HISER AND EDGAR N. LUPFER, OF SPRINGFIELD, OHIO, ASSIGNEES TO THE SPRINGFIELD METALLIC CASKET COMPANY, OF SAME PLACE.

DESIGN FOR A BURIAL-VAULT END.

SPECIFICATION forming part of Design No. 33,977, dated January 22, 1901.

Application filed November 27, 1900. Serial No. 37,936. Term of patent 7 years.

To all whom it may concern:

- Be it known that we, CHARLES H. HISER and EDGAR N. LUPFER, citizens of the United States, residing at Springfield, in the county of Clark and State of Ohio, have invented and produced a new and original Design for Burial-Vault Ends, of which the following is a specification, reference being had to the accompanying drawings, forming part thereof.
- 10 Figure 1 is an outside view of a burial-vault end, showing our new design. Fig. 2 is a sectional view taken on the line X X of Fig. 1, and Fig. 3 is a sectional view taken on the line Y Y of same figure.
- 15 As shown in the drawings, the leading or material feature of our design consists of a series of ribs a' on the upper portion a of the vault end, disposed or arranged as shown in Fig. 1, in connection with a series of ribs b', 20 arranged across the lower portion b of the vault end, as shown in said figure. The

ribs a' are arranged around the slightly-
raised outer edge of the upper portion of said
end, so as to leave an inner panel a², and are
formed on the outer surfaces by pressing, 25
stamping, or otherwise, the ribs b' being simi-
larly formed. Flanges c c' are adapted to
overlap at the point where the upper and
lower portions join.

Having described our invention, what we 30
claim as new, and desire to secure by Letters
Patent, is—

The design for a burial-vault end as herein
shown and described.

In testimony whereof we have hereunto set 35
our hands this 21st day of November, A. D.
1900.

CHARLES H. HISER.
EDGAR N. LUPFER.
